UNITED STATES PATENT OFFICE.

JOHN J. DEWEY, OF CINCINNATI, OHIO, ASSIGNOR TO THE AMERICAN LAUNDRY MACHINERY COMPANY, OF NORWOOD, OHIO, A CORPORATION OF OHIO.

DRYING APPARATUS.

Application filed January 12, 1918, Serial No. 211,531. Renewed May 23, 1922. Serial No. 563,125.

To all whom it may concern:

Be it known that I, JOHN J. DEWEY, citizen of the United States, residing at Cincinnati, in the county of Hamilton and State of Ohio, have invented certain new and useful Improvements in Drying Apparatus, of which the following is a specification.

This invention relates to drying apparatus and particularly to what are known as drying tumblers embodying a rotary foraminous cylinder in which the clothing, fabrics or other materials or articles to be dried are tumbled while circulating heated air therethrough to remove the moisture.

One object of the invention is to provide improved apparatus of this kind which conserves heat and reduces the steam consumption, whereby the apparatus can be operated at lower cost than heretofore. Another object of the invention is to enable the operator to load or unload the cylinder without stopping the air circulating fan but nevertheless without liability of blowing a blast of hot air into the face of the operator. A further object of the invention is to provide improved apparatus of this kind in which the circulating air current may be diverted at will either to flow through the heating chamber and then to the cylinder, or entirely to the outside air, so as to prevent loss of heat in the heating chamber while manipulating the goods in the cylinder. A further object of the invention is to provide improved drying apparatus in which the path of movement of the air current is automatically controlled by the outer casing door, so that without attention by the operator the air current is directed either through the drying cylinder during running condition or to the outside air while loading or unloading the cylinder.

Further objects of the invention are in part obvious and in part will appear more in detail hereinafter.

In the drawings, which represent one preferred embodiment of the invention, Fig. 1 is a sectional elevation on the line 1—1 Fig. 3; Fig. 2 is a front elevation, partly broken out and in section, of the lower portion of the apparatus; Fig. 3 is a sectional plan view on the line 3—3 Fig. 1; and Fig. 4 is a detail sectional elevation, on the line 4—4 Fig. 1, showing two positions of the air controlling door or gate.

The present invention is an improvement upon the drying tumbler described, shown and claimed in a prior application of Edward I. Cutter for drying apparatus, filed June 19, 1916, Serial Number 104,545. In many respects the present apparatus is like that of the prior application referred to, to which reference may therefore be had for a more complete description of said apparatus.

As illustrated in the drawings the apparatus comprises an outer casing or jacket 1 provided at its front with a hinged door or cover 2 closing an opening enabling the operator to gain access through the wall of the casing to the rotary foraminous drying cylinder 3 provided with a hinged door or doors 4 and supported upon the shaft 5. In said cylinder are the usual baffles 6 for tumbling the goods. By bringing the cylinder door 4 into registering relation with the casing door 2 access is afforded to the interior of the cylinder for loading or unloading the same.

At the back of the casing is a heating chamber 7 containing the usual pipe coils 8 connected to a source of heating medium, such as steam. Air circulating around said pipes is led to the heating chamber through a passage 9 communicating through an opening 10 with the drying chamber in which rotates the cylinder 3. The heated air discharged into the drying chamber passes through the foraminous cylinder and the goods therein and is discharged at the lower portion of said chamber through an opening 11 into the screening chamber 12 located at the front of the casing below the cylinder. Said chamber is provided with a suitable air inlet, such as the screened openings 13 located at either end of said chamber. One wall of said chamber such as the bottom wall, consists of a removable screen 14, through which the air current flows to the fan chamber 15 in the bottom of the casing and extending back beneath the drying chamber. Screen 14 is a removable member resting on suitable supports in the casing and removable through its front wall by opening the door 16, thereby enabling said screen to be readily cleaned and freed from lint or other foreign substances which may collect thereon.

In the fan chamber are located one or more air circulating devices 17, such as air

2
pumps, fans or blowers, two being illustrated. These fans are shown as of the centrifugal type, having their rotors 18 mounted upon a shaft 19. The fan inlets 20 are open to the fan chamber 15, while their outlets communicate with a passage 21 extending rearwardly in the casing beneath the heating chamber 7 and communicating through the rear wall of the casing with an outlet pipe 22, which may discharge into the atmosphere or may be connected to a conduit leading to a remote point, as desired.

At the bottom of the heating chamber 7 is a gate or door 23 movable to two positions shown in full and dotted lines Fig. 1, preferably by being hinged to the wall of the casing, as at 24. In the loading position, shown in full lines, this door closes or cuts off communication from the passage 21 to the heating chamber, so that all of the air discharged from the fans is directed through the passage 21 to the outlet 22 and thence into the outside air or into a conduit leading to any suitable point. Also, when door 2 is open, the suction of the fans is effective in the drying chamber so that there is a rush or flow of atmospheric or unheated air through the door opening into the drying chamber and thence to the fans and to the outlet. This inflowing atmospheric air cools down and freshens up the clothes which have just been dried. In the running or drying position, shown in dotted lines, the door 25 forms a deflector which diverts a portion of the air into the heating chamber and the balance to the outlet. To split the air current the door is preferably provided with one or a plurality of spaced curved feet 24', 40 which support the door in the running position with its front edge 25 elevated above the floor of the passage 21. This arrangement diverts to the outlet 22 the heavier moisture laden air which naturally travels near the bottom of the passage 21, and the lighter drier air to the heating chamber, from which it is circulated through the drying cylinder. As will be readily understood when the tumbler is loaded and closed and the fans are running, a certain quantity of air is drawn in at the inlets 13 and circulated through the apparatus, and a portion of the air is continually discharged at the outlet. The greater quantity of air however, 55 is circulated again and again through the cylinder, finally reaching the outlet when it has absorbed its portion of the moisture in the goods.

In the use of apparatus of this kind it is customary to unload and load the cylinder without stopping the fan, and as the doors 2 and 4 are large as compared with the normal outlet to the atmosphere, the rotating fans drive a heavy current of hot air into the face of the operator working at the

doors. In the present apparatus, when the doors 2 and 4 are opened to load or unload the cylinder the gate 23 is moved to the closed position shown in full lines Fig. 1, so that all of the air delivered by the fans 70 is discharged to the atmosphere. The heating chamber is therefore cut out of the circulating system and no condensing effect occurs in the steam pipes therein, thereby conserving heat and steam and at the same 75 time preventing outward flow of air at the loading door. Preferably also the present apparatus includes means or mechanism for automatically governing the position of the current controlling gate 23 by the position of 80 the door 2, so that the direction of flow of air is adjusted without attention by the operator. For this purpose the gate 23 is pivotally connected to a rod or link 26 extending upwardly through the heating chamber 85 to the top of the apparatus, where it passes through a frame guide 27. 28 indicates a bracket carrying a bell crank lever, one arm 29 of which is forked to embrace the rod 26, said bracket arm being provided with a recess or seat 30 to receive a cross pin 31 connected to rod 26 lying beneath the adjustable lock nuts 32 thereon. 33 indicates lock nuts carried by the rod 26 lying beneath the arm of said lever. The other arm 34 of said 95 lever is pivotally connected to a rod 35 extending through a guide 36 to the front of the machine where it is provided with an antifriction member, such as the roller 37 for engagement by the door 2. 100

When the door 2 is closed and the machine running, the gate 23 drops by gravity and moves its actuating mechanism to the position shown in dotted lines. When the door 2 is opened it is pushed back to the 105 position shown in full lines Fig. 1 thereby pushing back the rod 35 and closing the gate 23. The weight of the door 2 is sufficient to hold the parts in this position while loading or unloading the apparatus. 110 The gate 23 can also be opened or closed by hand, when desired or necessary by manually pushing or pulling on the rod 35. 115

The heating effect of the coils 8 is quite pronounced, as a consequence of which said coils carry considerable heat at all times. It is therefore desirable to not only save this heat by cutting off the circulation of air over the coils when loading or unloading the machine, but also to prevent radiation 120 of the heat in other ways. One possible loss of heat is by radiation from the upper portion of the heating chamber when the door 2 is open. To prevent this loss the upper portion of the heating chamber may 125 be provided with an automatic damper or door, such as indicated at 38. This damper is a light sheet metal member hinged at 39 to the upper wall of the casing and of proper shape to wholly close or seal the heating 130

- chamber when the damper is in the position shown in full lines Fig. 1. This is the position of damper 38 when the door 23 is closed, and in this position all the heat of the coils is bottled up in the heating chamber. The door assumes this position by gravity. However, when the door 23 is moved to the dotted line position Fig. 1 the current of air passing through the heating chamber 10 pushes back or raises the damper 38 to the position shown in dotted lines, thereby permitting a free flow of air to the drying chamber.

What I claim is:—

1. Drying apparatus, comprising a casing provided with a drying chamber in its upper portion, a heating chamber behind the drying chamber and a passage leading to an outlet, an air circulating device located beneath the drying chamber and communicating with said passage, a screen chamber located between the drying chamber and device, and a movable member arranged in one position to divert a portion of the air 20 to said heating chamber and a portion to the outlet and in another position to close communication between said passage and the heating chamber.

2. Drying apparatus, comprising a casing

- 30 provided with a drying chamber in its upper portion, a heating chamber behind the drying chamber and a passage leading to an outlet, an air circulating device located beneath the drying chamber and communicating with said passage, a screen chamber located between the drying chamber and device, a movable member arranged in one position to divert a portion of the air to said heating chamber and a portion to the outlet 40 and in another position to close communication between said passage and the heating chamber, and an air inlet to said casing between said device and drying chamber.

3. Drying apparatus, comprising a casing

- 45 provided with a heating chamber, a drying chamber having an opening, a screen chamber, means for circulating air through said chambers, a door closing the opening to said drying chamber and an outlet, and means controlled by said door for diverting the air current from said chambers to an outlet.

4. Drying apparatus, comprising a cas-

- 55 ing containing a heating chamber, means for circulating air through said chamber, a door for said casing, and means controlled by said door for regulating the path of movement of the air current.

5. Drying apparatus, comprising a casing

- 60 provided with heating and drying chambers, a door closing an opening to said drying chamber, means for circulating air through said chambers, and means controlled by said door arranged when said door is opened to close the heating chamber.

6. Drying apparatus, comprising a casing

having a heating chamber and a drying chamber, an air circulating device having an outlet communicating with said heating chamber and with the atmosphere, a door for said drying chamber, and means controlled by the position of said door for diverting the air current from said device either to said heating chamber or to the atmosphere.

7. Drying apparatus, comprising a casing 75 provided with a drying chamber and a heating chamber, an air circulating device arranged to withdraw air from said drying chamber and communicating with a passage lying adjacent the heating chamber and leading to an outlet, a door adapted to close an opening leading from said passage to the heating chamber, a door covering an opening to the drying chamber, and operating connections between said doors.

8. Drying apparatus, comprising a casing 80 provided with a drying chamber and a heating chamber, and an air circulating device arranged to withdraw air from said drying chamber and communicating with a passage 85 lying adjacent the heating chamber and leading to an outlet, a door adapted to close an opening leading from said passage to the heating chamber, a door covering an opening to the drying chamber, and operating 90 connections between said doors and arranged so that when the last named door is opened the first named door is closed.

9. Drying apparatus, comprising a casing 95 provided with a drying chamber and a heating chamber, an air circulating device arranged to withdraw air from said drying chamber and communicating with a passage 100 lying adjacent the heating chamber and leading to an outlet, a door adapted to close an opening leading from said passage to the heating chamber, a door covering an opening to the drying chamber, and operating 105 connections between said doors and arranged so that when the last named door is opened the first named door is closed and vice versa.

10. Drying apparatus, comprising a casing 110 provided with a heating chamber, a drying chamber and a screen chamber, means for circulating air through the heating 115 chamber to the drying chamber, and means for closing communication between the heating and drying chambers when the circulation of air between them ceases.

11. Drying apparatus, comprising a casing 120 provided with a heating chamber, a drying chamber, and a screen chamber, means for circulating air from the heating chamber to the drying chamber, and means controlled by the flow of air through said chambers for closing communication between the heating and drying chambers when the circulation of air between them ceases.

12. Drying apparatus, comprising a cas-

- 4
- ing provided with a heating chamber, a drying chamber and a screen chamber, a device for circulating air through said chambers, means for diverting the flow of air from said chambers to the atmosphere, and means for closing communication between the heating and drying chambers when the air current flows to the atmosphere. 5
13. Drying apparatus, comprising a casing provided with a heating chamber, a drying chamber and a screen chamber, and means for closing both ends of said heating chamber. 10
14. Drying apparatus, comprising a casing provided with a heating chamber and a drying chamber, means for circulating air through said chambers, and a gravity controlled damper for closing communication between said chambers when the circulation 15 of air between them ceases. 20
15. Drying apparatus, comprising a casing provided with a drying chamber and a heating chamber and a passage leading to an outlet, an air circulating device located in said casing and communicating with said passage, and a movable member arranged in one position to divert a portion of the air to said heating chamber and a portion to said passage and in another position to close 25 communication between said passage and the heating chamber. 30
16. Drying apparatus, comprising a casing provided with a heating chamber and a drying chamber, means for circulating air through said chambers, regulating dampers one at the entrance to and one at the exit from the heating chamber, one of said dampers being normally closed by gravity, and operating means for the other damper. 35
- 40 17. Drying apparatus, comprising a casing provided with a heating chamber and a drying chamber, means for circulating air through said chambers, a normally operable damper for controlling the flow of air from the heating chamber to the drying chamber, and another damper for controlling the flow of air from the drying chamber to the heating chamber, said last named damper being normally closed by gravity and opened by the flow of air between said chambers. 45 50
18. Drying apparatus, comprising a casing provided with a heating chamber and a drying chamber, a door for said casing, means for circulating air through said chambers and means controlled by said door for regulating the flow of air between said chambers. 55
19. Drying apparatus, comprising a casing provided with a heating chamber, a drying chamber, and a fan chamber, and means for closing both ends of the heating chamber. 60
20. Drying apparatus, comprising a casing provided with a heating chamber, a drying chamber, and a fan chamber, and means adapted in one position to cause circulation of heated air from the heating chamber through the drying chamber and in another position to cut off said circulation and cause circulation of unheated air through the drying chamber. 65 70
21. Drying apparatus, comprising a casing provided with a heating chamber, a drying chamber, a fan chamber, means for closing communication between the fan chamber and heating chamber, an operating device therefor, and a damper controlling communication between the heating chamber and drying chamber and adapted to be closed when communication between the fan chamber and heating chamber is cut off. 75 80

In testimony whereof I affix my signature.

JOHN J. DEWEY.

Certificate of Correction.

It is hereby certified that in Letters Patent No. 1,488,198, granted March 25, 1924, upon the application of John J. Dewey, of Cincinnati, Ohio, for an improvement in "Drying Apparatus," errors appear in the printed specification requiring correction as follows: Page 3, line 47, claim 3, after the syllable "ber" and before the comma insert the words *and an outlet*; line 49, strike out the words "and an outlet", and line 51, for the article "an" read *the*; and that the said Letters Patent should be read with these corrections therein that the same may conform to the record of the case in the Patent Office.

Signed and sealed this 20th day of May, A. D. 1924.

[SEAL.]

KARL FENNING,
Acting Commissioner of Patents.
